(57) **CLAIM**

We claim the ornamental design for a display board, as shown and described.

DESCRIPTION

FIG. 1 is a front perspective view of a first embodiment of a display board of the present invention.

FIG. 2 is a front view of the display board of FIG. 1.

FIG. 3 is a top view of the display board of FIG. 1.

FIG. 4 is a bottom view of the display board of FIG. 1.

FIG. 5 is a right-side view of the display board of FIG. 1.

FIG. 6 is a left-side view of the display board of FIG. 1.

FIG. 7 is a rear view of the display board of FIG. 1.

FIG. 8 is a front perspective view of a second embodiment of a display board of the present invention.

FIG. 9 is a front view of the display board of FIG. 8.

FIG. 10 is a top view of the display board of FIG. 8.

FIG. 11 is a bottom view of the display board of FIG. 8.

FIG. 12 is a right-side view of the display board of FIG. 8.

FIG. 13 is a left-side view of the display board of FIG. 8.

FIG. 14 is a rear view of the display board of FIG. 8.

FIG. 15 is a front perspective view of a third embodiment of a display board of the present invention.

FIG. 16 is a front view of the display board of FIG. 15.

FIG. 17 is a top view of the display board of FIG. 15.

FIG. 18 is a bottom view of the display board of FIG. 15.

FIG. 19 is a right-side view of the display board of FIG. 15.

FIG. 20 is a left-side view of the display board of FIG. 15.

FIG. 21 is a rear view of the display board of FIG. 15.

FIG. 22 is a front perspective view of a fourth embodiment of a display board of the present invention.

FIG. 23 is a front view of the display board of FIG. 22.

FIG. 24 is a top view of the display board of FIG. 22.

FIG. 25 is a bottom view of the display board of FIG. 22.

FIG. 26 is a right-side view of the display board of FIG. 22.

FIG. 27 is a left-side view of the display board of FIG. 22; and,

FIG. 28 is a rear view of the display board of FIG. 22.

The broken lines on the rear in FIGS. 7, 14, 21, and 28 are included for the purpose of illustrating environment and form no part of the claimed design.

The stippling shown in the drawings of FIGS. 15, 16, 22, and 23 represents a contrast of material.

1 Claim, 18 Drawing Sheets
